UNITED STATES PATENT OFFICE.

HUGO KAFKA, OF NEW YORK, N. Y.

FIRE-ESCAPE.

SPECIFICATION forming part of Letters Patent No. 291,198, dated January 1, 1884.

Application filed July 20, 1883. (No model.)

To all whom it may concern:

Be it known that I, HUGO KAFKA, of the city, county, and State of New York, have invented certain new and useful Improvements 5 in Fire-Escapes, of which the following is a specification.

This invention has reference to an improved fire-escape that is permanently attached to the buildings, and which has, besides, a very 10 ornamental character, so as to be applicable in all cases in which a common fire-escape would be highly objectionable.

The invention consists of ladders which connect the balconies of the several stories, and 15 are covered by panels of lattice-work arranged in front of and parallel to the ladders, the cross-ribs of the panels being arranged at a level, or nearly so, with the rungs of the ladders. The panels of lattice-work extend, also, 20 at a suitable angle to the ladders, so as to form a screen and guard-rail for the same.

The invention consists, further, of certain details of construction, which will be described hereinafter.

25 In the accompanying drawings, Figure 1 represents a front elevation of a building with my improved fire-escape. Fig. 2 is a vertical transverse section of the same. Figs. 3 and 4 are detail vertical transverse sections of a balcony and connecting-ladders, and Figs. 5 and 30 6 are plans of Figs. 3 and 4.

Similar letters of reference indicate corresponding parts.

A in the drawings represents balconies of ornamental cast-iron work, arranged for the several stories of the building. The balconies A. A. are supported on brackets B B, which are firmly anchored into the wall of the building. The balconies are connected at their ends by 40 vertical or inclined ladders C, that are either placed at right angles to or parallel with the wall of the building and that communicate with openings a a in the balconies A. A. To hide the ladders C, panels C', of ornamental lattice-work, are arranged in front of the ladders and additional panels, C'', of lattice-work at suitable angles to the former, which panels form a body of lattice-work that has the appearance of pillars supporting the balconies, 45 as shown in Fig. 1. The panels C' serve as a screen for the ladders, while the panels C''

serve as a guard-rail for the persons descending on the vertical ladders C, so that they are prevented from getting dizzy and from falling from the ladder. The cross-ribs of the panels 55 C' C'' are so located relatively to the rungs of the ladders that they are on a level, or nearly so, with the rungs, as shown in Figs. 3 and 4, whereby they form an additional support for the feet. 60

Instead of conducting the escape-ladders C in one continuous flight through the balconies, I prefer to break the same into sections and arrange one section close to the wall of the building and the next below farther away 65 from the wall, next to the front railing of the balcony, by which arrangement parties descending are compelled when arriving on the balconies to step sidewise on the balcony to the opening a and the ladder leading to the 70 next balcony below, whereby they are prevented from seeing the persons following them from above, and have always a closed balcony-floor in sight below them.

The front lattice-work, C'', may also be used 75 as a ladder in case of need, though in most cases this would not be required, as two ladders—one at each end of the balcony—are sufficient for the escape of the persons in danger.

A fire-escape constructed according to my improved method can be applied after the building is completed, or while the same is in course 80 of erection, and presents an ornamental appearance, especially when its design is in keeping with the architecture of the building. It forms 85 a substitute for the unsightly fire-escape ladders generally in use, and can be used in a convenient manner and without any danger, not only by grown persons, but also by women and children. The ladders and screens also 90 give additional strength and rigidity to the balcony-railings, as the latter are secured to the ladders and panels at different points.

Having thus described my invention, I claim 95 as new and desire to secure by Letters Patent—

1. An improved fire-escape for buildings, consisting of balconies for the several stories, ladders connecting the same, and panels of lattice-work arranged in front of and parallel to the ladders, the cross-ribs of the panels being arranged at a level, or nearly so, with the rungs of the ladder, substantially as set forth. 100

2. An improved fire-escape for buildings, consisting of balconies for the several stories, ladders connecting the balconies, and panels of lattice-work extending in front of and at 5 suitable angles to the ladders, so as to form a screen and guard-rail for the same, substantially as set forth.
3. An improved fire-escape for buildings, consisting of balconies for the several stories, 10 said balconies having an opening or openings alternately closer to or farther from the wall of the building, ladders made in sections and

communicating alternately with said openings, and panels of lattice-work arranged in front of and at a suitable angle to the ladders, so 15 as to form a screen and railing for the same, substantially as set forth.

In testimony that I claim the foregoing as my invention I have signed my name in presence of two subscribing witnesses.

HUGO KAFKA.
